UNITED STATES PATENT OFFICE

148,351

DESIGN FOR A BRACELET

Conrad Dallwin Hamilton, New York, N. Y.

Application August 3, 1946, Serial No. 132,263

Term of patent 7 years

(Cl. D45—4)

To all whom it may concern:

Be it known that I, Conrad Dallwin Hamilton, a citizen of the United States, residing at New York, in the county of New York and State of New York, have invented a new, original, and ornamental Design for a Bracelet, of which the following is a specification, reference being had to the accompanying drawing, forming part thereof.

I claim:

The ornamental design for a bracelet, as shown.

CONRAD DALLWIN HAMILTON.
